CLAIM

The ornamental design for a mechanic's creeper, as shown and described.

DESCRIPTION

FIG. 1 is a top plan view of a mechanic's creeper showing our new design;

FIG. 2 is a front elevational view thereof;

FIG. 3 is a rear elevational view thereof;

FIG. 4 is a side elevational view thereof, the opposite side view being a mirror image of that shown;

FIG. 5 is a bottom plan view thereof, and,

FIG. 6 is a top front perspective view thereof.

The material shown in phantom in FIG. 6 is intended to show a use of the mechanic's creeper only and does not form a part of the inventive design.
